HEAT EXCHANGE APPARATUS

John F. Thunstrom, New York, N. Y., assignor to Foster Wheeler Corporation, New York, N. Y., a corporation of New York

Application August 11, 1955, Serial No. 527,678

4 Claims. (Cl. 122—478)

This invention relates to fluid heat exchange apparatus and more particularly to tubular support arrangements for such apparatus.

In fluid heat exchange apparatus, as for example, vapor generators, supports for fluid conducting tubular members have always presented considerable maintenance problems, one of the reasons being the poor grade of present day fuels. This is especially true in the case of superheaters. Numerous types of supports have been proposed but the majority depend upon some type of metallic member other than the tubing to support the superheater elements. The supports have corroded and failed repeatedly after only short service because the cooling of the members in the hot gas zone is limited to the low heat transfer afforded by conduction through the metallic member to the tube wall. The problems due to the corrosion of the members have been accentuated by the extreme difficulty experienced in the complicated and tedious procedure of replacing the members.

The present invention contemplates a novel support for fluid conducting tubular members in fluid heat exchange apparatus and particularly to superheaters therein. The support is achieved by using only the boiler and superheater tubes, and a portion of the boiler tubes and the superheater tubes are shaped to provide the sole means of supporting and spacing the superheater tubes. Spacing of the superheater tubes is accomplished by alternating a row of superheater tubes between specially bent boiler tubes. The specially bent rows of boiler tubes immediately precede and follow the superheater in the direction of gas flow. A minimum clearance transverse of the direction of gas flow is provided between the superheater elements and boiler tubes to hold the elements in proper location and the clearance is such that it will permit the superheater elements to expand at a rate other than that of the boiler spacer tubes.

The foregoing advantages of the present invention will appear more fully hereinafter from a consideration of the detailed description which follows, taken together with two embodiments of the invention which are illustrated by way of example.

In the drawings:

Fig. 1 is an elevational view, in section, of a vapor generator having one embodiment of the novel support therein;

Fig. 2 is an enlarged fragmentary view, in elevation, of the novel support means of Fig. 1;

Fig. 3 is a top plan view of the support of Fig. 2;

Fig. 4 is a sectional view taken along the line 4—4 of Fig. 2;

Fig. 5 is a fragmentary view, in elevation, of the vapor generator of Fig. 1 but discloses a second embodiment of the present invention;

Fig. 6 is a fragmentary view, in elevation, of the support of Fig. 5;

Fig. 7 is a top plan view of the support of Fig. 5; and

Fig. 8 is a sectional view taken along the line 8—8 of Fig. 6.

2

Referring now to the drawings and more particularly to Fig. 1 thereof wherein one embodiment of the present invention is clearly illustrated, the numeral 11 generally designates a vapor generator which comprises a setting 12 and a roof portion 12A. The vapor generator 11 is illustrated for purposes of explanation as a marine vapor generator but it is to be understood that the subject invention is readily applicable to other types of vapor generators. A furnace, or combustion chamber 13, is provided in setting 12 and the walls of the combustion chamber are lined with boiler tubes 14. The upper ends of boiler tubes 14, along a rear wall 15, are connected to an inclined header 16 (shown in broken lines) adjacent roof portion 12A, which header in turn communicates with a vapor and liquid vessel 17 in the upper portion of the setting by means (not shown); the boiler tubes 14, along a side wall 18, thence extending parallel to roof portion 12A and being directly connected to vessel 17. The lower ends of boiler tubes 14 along rear wall 15 are connected to a header 19 disposed at the bottom of setting 12 and the header, in turn, is connected to a water header 19A by floor tubes (not shown) to receive liquid therefrom. A header 20, also connected by the floor tubes (not shown) to header 19A, is disposed at the bottom of side wall 18 and is connected to the boiler tubes along said wall.

A plurality of substantially vertical, but slightly inclined, boiler screen tubes 21 are arranged on the side of combustion chamber 13 opposite side wall 18 and extend from the front wall of setting 12 to rear wall 15. Tubes 21 are arranged in three parallel rows 22, 23 and 24, respectively; the tubes in row 22 being closest to the furnace. The upper ends of tubes 21 are connected to the lower portion of vapor and liquid drum 17 while the lower ends of the tubes are connected to water header 19A. Header 19A receives water through conduits 25 (one shown) connected to a water drum 26 which, in turn, receives water from vapor and liquid vessel 17 by a plurality of convection tubes 27 and downcomers not shown. Convection tubes 27 are spaced from tubes 21 and substantially parallel therewith and are connected at their upper ends with vessel 17 and at their lower ends to water drum 26. Tubes 27, as do tubes 21, extend from the front wall (not shown) to the rear wall 15. Two rows 28 and 29 of tubes 27 are bent at their upper ends differently from the remaining tubes 27, for a purpose to be brought out presently.

A superheater 30 is disposed in the space between tubes 21 of row 24 and tubes 27 of row 28 and comprises superheater tubes or elements 31. Superheater tubes 31 are arranged substantially vertically but slightly inclined and the ends of each tube are arranged adjacent each other for connection to a superheater inlet header 32 and a superheater outlet header 33. Each superheater tube 31 comprises a pair of legs 34 and 35 which are disposed substantially parallel with each other. The intermediate portion of each tube 31 extends substantially transversely of the legs and is arcuate-shaped or in the form of a loop. Leg 34 of superheater tube 31 is substantially straight throughout its entire length and merges into the arcuate intermediate portion, while leg 35 is substantially straight to a point vertically below the point where leg 34 merges into the arcuate portion; leg 35 thereafter is inclined toward opposite leg 34 to merge into the arcuate portion adjacent the last mentioned point. As indicated in Figs. 2 to 4 superheater tubes 31 are arranged in parallel planes which are horizontally spaced. Tubes 31 are arranged in a predetermined pattern wherein the tube in one plane is rotated 180° from the position of the superheater tubes in the preceding and succeeding planes (Fig. 2). Additional superheating tubes 31 are arranged within the space en-

compassed by superheater tubes 31 as to be nested therein. Corresponding adjacent portions of legs 34 of superheater tubes 31 engage each other adjacent the intermediate portion of the tubes, while corresponding adjacent portions of legs 35 of superheater tubes 31 engage each other below the point where the legs are inclined. Each outermost superheater tube 31 has provided coplanar therewith a tube 21 of rows 23 or 24 and a tube 27 of rows 28 or 29. As seen in Fig. 3, the first plane containing superheater tubes 31 has the outermost tube engaged by a boiler tube 21 in row 24, which boiler tube then extends parallel to the inclined portion of the superheater tubes (Fig. 2). Leg 34 of the outermost superheater tube 31 in the last-mentioned plane is engaged by a tube 27 in row 29 and by reason of the foregoing, the superheater tubes 31 in each plane are supported. In the next following plane leg 34 of the outermost tube 31 is engaged by tube 21 in row 23, and leg 35 of tube 31 in the same plane is engaged by tube 27 in row 28. It will be noted that tubes 21 of row 24 and tubes 27 of row 28 extend transversely of or across the superheater tubes 31 to some extent, and on both sides of the nested tubes, to thereby prevent lateral movement of the latter. In this manner, motion of the superheater tubes 31 is constrained in all directions except lengthwise along the superheater tubes to permit thermal expansion of the latter. Furthermore, the superheater tubes are bent in a manner that they bear upon the tubes 21 and 27 for a short distance to provide for the transmission of a portion of the load to the latter.

A flue 38 is formed in the upper portion of the setting 12 for discharging combustion gases from the latter and an economizer 39 is disposed in flue 38.

In operation, combustion gases formed in combustion chamber 13 pass over tubes 21 and in heat exchange relationship therewith thence over superheater tubes 31 and convection tubes 27. The combustion gases then flow out of the setting through flue 38 and in heat exchange relationship with economizer 39. The water in drum 17 flows downwardly through the downcomers (not shown) and through some of the tubes 27 into water drum 26. From drum 26 a portion of the water flows into the remaining tubes 27 where a steam and water mixture is formed which flows into drum 17. Water from drum 26 also flows into header 19A through conduits 25 and a portion of the water thereafter flows upwardly into tubes 21 where a mixture of steam and water is formed which flows into drum 17. Water in header 19A also flows through the floor tubes (not shown) for collection in headers 19 and 20 whence the water flows upwardly in boiler tubes 14 for entry into header 16 and drum 17 as a steam and water mixture. The steam collected in vessel 17 is then conducted by means (not shown) to superheater inlet header 32, whence the steam passes through the superheater tubes 31 where the steam is superheated, and the superheated steam is collected in outlet header 33. From outlet header 33 the steam is conducted to steam utilization apparatus (not shown).

Figs. 5 to 8 illustrate a second embodiment of the present invention and differs from the first embodiment in that the second embodiment provides for two sets of nested superheater tubes in each parallel plane. Since the screen boiler tubes 21 and convection tubes 27 of the first embodiment are substantially identical in function and structure with the corresponding tubes in the second embodiment, the reference characters designating such tubes is retained in the description of the second embodiment. In the second embodiment, a superheater assembly 42 is provided in the space between tubes 21 of row 24 and tubes 27 of row 28. Superheater 42 comprises superheater tubes 43 and 44 which are coplanar and pairs of the latter are arranged in horizontally spaced parallel planes. In the first plane containing both superheater tubes 43, 44 as seen in Figs. 5 to 8, superheater

tube 43 includes a pair of substantially parallel legs 45 and 46 while superheater tube 44 includes a pair of substantially parallel legs 47 and 48. The end of leg 45 of superheater tubes 43 is secured to a superheater inlet header 49 while the end of leg 46 is secured to an intermediate superheater header 50 arranged above header 49 as shown in Fig. 5. The end of leg 47 of superheater tube 44 is secured to intermediate superheater header 50, while the end of leg 48 is secured to an outlet superheater header 51. The intermediate portions of superheater tubes 43 and 44 are substantially in the form of loops, or arcuate shaped, which extend substantially transversely of their respective legs. Legs 45 and 46 of superheater tubes 43 are substantially straight throughout their respective lengths except adjacent the intermediate portion where leg 45 is bent into engagement with tube 21 of row 23 (Figs. 5 and 6). Legs 47 and 48 of superheater tubes 44 are substantially straight to a point vertically below the point where leg 45 is bent into engagement with the tube 21. Legs 47 and 48 of superheater tubes 44 are inclined from the first-mentioned point toward superheater tube 43 and in engagement with the latter as seen in Fig. 6. In the first-mentioned plane superheater tube 43 is provided with an inner nested tube which is similarly shaped and in engagement with tube 43 adjacent the point where the latter engages tube 21. A portion of leg 48 of superheater tube 44 engages convection tube 27 of row 28 adjacent the second mentioned point. An inner superheater tube is arranged within the space encompassed by superheater tube 44 and is shaped in substantially the same manner as the latter. The legs of the inner superheater tubes engage and bear on the legs 47 and 48 of the outer superheater tube 44 adjacent the point where tube 44 engages convection tube 27 of row 28. Tube 27 of row 28 is inclined from the mentioned point of engagement to extend substantially parallel to the upper portions of legs 47 and 48 for a short distance and then substantially vertically for connection with vessel 17. Tubes 43 and 44 are arranged in a pattern wherein the tubes in one plane, other than the first mentioned plane, are rotated 180° from the positions in the preceding and succeeding planes so as to provide a substantially criss cross pattern. Thus, in the next succeeding plane the ends of leg 45 of superheater tubes 43 are connected to outlet header 51 and the ends of leg 46 are connected to intermediate header 50. In like manner, the ends of leg 47 are connected to intermediate header 50 and the ends of leg 48 are connected to inlet header 49. In order to restrain lateral movement of the superheater tubes 43 and 44 a pair of tubes 21 and 27 of rows 24 and 28, respectively, are arranged on each side of planes containing the superheater tubes 43 and 44.

In the foregoing construction a portion of the load of superheater tubes 43 and 44 is transmitted to tubes 21 and 27 and in addition a portion of the load of the inner nested tubular members is transmitted through tubes 43 and 44 to the tubes 21 and 27.

The operation of the second embodiment of the present invention in a vapor generator is identical with that of the first embodiment and the combustion gases from the combustion chamber pass first in contact with tubes 21 of rows 23 and 24, thence in contact with superheater tubes 43 and 44, whence the gases pass in contact with tubes 27 of rows 28 and 29.

It will now be apparent that the present invention provides a novel tubular arrangement for fluid heat exchange apparatus. In the case of a vertical superheater, no hangers or other metallic elements are required for supporting the superheater tubes because of the contacting predetermined shaped tubes which support each other.

Although two embodiments of the present invention have been illustrated and described in detail, it is to be expressly understood that the invention is not limited thereto. Various changes can be made in the design and

arrangement of the parts without departing from the spirit and scope of the invention as the same will now be understood by those skilled in the art.

What is claimed is:

1. In a tubular arrangement for fluid heat exchangers, a substantially vertical first fluid conducting tubular member having fixed ends adjacent to one another and having a pair of coplanar legs substantially parallel with each other, one of said legs being substantially straight and merging into an upper loop and intermediate portion while the second leg is substantially straight and to a point vertically below the point on said one leg where the latter merges into the loop portion, said second leg being inclined toward said one leg from the first-mentioned point and merging into the other side of the loop portion, a second vertical fluid conducting tubular member disposed along each leg of said first tubular member and coplanar therewith, the second tubular member along said one leg being spaced from the latter except adjacent the second-mentioned point where it extends toward and in engagement with said one leg, the second tubular member along said second leg being spaced from the latter except adjacent the first-mentioned point where it engages said second leg, said last-mentioned second tubular member thereafter being inclined and arranged parallel to the inclined portion of said second leg, and a pair of substantially vertical third fluid conducting tubular members arranged in parallel planes, one of said third tubular members being on one side of the plane containing the first and the second fluid conducting tubular members and the other third tubular member being on the other side of said plane for preventing lateral movement of said first fluid conducting tubular member transversely of said third fluid conducting tubular members.

2. In a tubular arrangement for fluid heat exchange apparatus, a plurality of horizontally spaced and substantially vertical first fluid conducting tubular members each of which have fixed ends adjacent to one another, each of said first tubular members having a pair of coplanar legs substantially parallel with each other, one of said legs being substantially straight and merging into an upper loop and intermediate portion while the second leg is substantially straight to a point vertically below the point on said one leg where the latter merges into the loop portion, said second leg being inclined toward said one leg from the first-mentioned point and merging into the other side of the loop portion, said first tubular members being arranged so that successive tubular members are rotated 180° from the preceding tubular members, and a second vertical fluid conducting tubular member disposed along each leg of said first tubular member and coplanar therewith, the second tubular member along said one leg of the first tubular member being spaced from the latter except adjacent the second mentioned point where it extends toward and in engagement with said one leg, the second tubular member along said second leg being spaced from the latter except adjacent the first-mentioned point where it engages said second leg, said last-mentioned second tubular member thereafter being inclined and ar-

ranged parallel to the inclined portion of said second leg and positioned adjacent the loop portions of the preceding and succeeding first tubular members to prevent lateral movement of the latter transversely of the inclined portion of the second tubular member.

3. The tubular arrangement set forth in claim 2 wherein additional vertical first fluid conducting tubular members are disposed coplanar with the first vertical tubular members and in the space encompassed by the latter as to 10 be nested therein, said additional tubular members having portions corresponding to the first and the second mentioned points on said legs engaging each other, and the outermost additional first tubular member engaging the first tubular member at the portions where the latter 15 engage the second tubular members.

4. In a tubular arrangement for fluid heat exchange apparatus, a plurality of pairs of substantially vertical first fluid conducting tubular members, each pair of tubular members being arranged in horizontally spaced 20 and parallel planes, each of said tubular members having fixed ends adjacent to each other and including a pair of substantially parallel legs, one of said pair of tubular members having the legs thereof substantially straight throughout their lengths except at the upper part where 25 the legs merge into a loop portion, the other of said pair of tubular members having legs substantially straight to a point vertically below the point where the legs of said one tubular member merges into the loop portion, the legs of said other tubular member being bent from 30 the first-mentioned point and inclined toward said one tubular member to merge into a loop portion, the portion of the tubular member adjacent said last-mentioned loop portion engaging said one tubular member adjacent the loop portion of the latter, said pairs of tubular members 35 being arranged so that successive pairs of tubular members are rotated 180° from the preceding tubular member, and a second vertical fluid conducting tubular member disposed along one leg of each of the pairs of first tubular members and coplanar therewith, the second tubular 40 member along said one leg of said one first tubular member being spaced from the latter except adjacent the second-mentioned point where the second tubular member engages said one leg of said one first tubular member, the second tubular members along the one leg of said other first tubular member being spaced from the latter except adjacent the first-mentioned point where they 45 engage the last-mentioned leg, said last-mentioned tubular members thereafter being inclined and arranged parallel to the inclined leg portions of said other first tubular member and preventing lateral movement of the preceding and succeeding one first tubular member.
